UNITED STATES PATENT OFFICE

112,807

DESIGN FOR AN OUTSIDE DOOR HANDLE

George E. Cossin, Detroit, Mich.

Application December 1, 1937, Serial No. 73,294

Term of patent 3½ years

To all whom it may concern:

Be it known that I, George E. Cossin, a citizen of the United States and a resident of Detroit, Michigan, have invented a new, original, and ornamental Design for an Outside Door Handle, of which the following is a specification, reference being had therein to the accompanying drawing, forming part thereof.

Figure 1 is a plan view of the outside door handle, showing my new design;

Figure 2 is an elevation of the same;
Fig. 3 is a section as if on line 3—3 of Figure 2.
The stippled portion in the drawing represents a black rubber insert.

What I claim is:
The ornamental design for an outside door handle, as shown and described.

GEORGE E. COSSIN.
